HOOD LATCH

Clarence F. Kramer, Birmingham, Mich., assignor
to Ford Motor Company, Detroit, Mich., a cor-
poration of Delaware

Application August 17, 1950, Serial No. 179,985

1. Claim. (Cl. 292—44)

1

This invention relates to hood latches for motor vehicles.

An object of the present invention is to provide a heavy duty hood latch particularly suited for use on trucks but also suitable for use on other motor vehicles as well. The hood latch is adapted to be released either directly by reaching through an opening in the radiator grille, or remotely by means of suitable remote controls. It contains a minimum of parts all of relatively simple construction, thus effecting economy in manufacture and assembly.

A further object of the invention is to provide a hood latch which is self-centering in operation to automatically center the hood transversely of the vehicle when the hood is closed.

Still another object of the invention is to provide a hood latch comprising a pair of cooperating interlocking cam members pivotally mounted for rotation about horizontal transversely spaced axes, the interlock between the two cam members insuring simultaneous operation both during the latching and unlatching operations. One of the cam members is engaged by a spring to automatically raise the hood a short distance when released, and the other is engaged by a suitable pawl to releasably hold the cam members in their latched position and also to limit the opening movement of the members. A U-shaped striker is used which permits longitudinal misalignment between the latch and striker without effecting the operation of the latch. Longitudinal movement of the hood in relation to the grille in the latched position is also permitted.

Another object of the invention is to provide a hood latch having a pair of cooperating pivoted cam members provided with jaw portions adapted to embrace the striker in the closed position of the hood, one of the cam members being provided with a projection directly beneath the jaw members in the path of movement of striker to be engaged thereby and to rotate the cam members and close the jaw portions thereof automatically during the closing movement of the hood. This arrangement retains the hood in a fixed lateral and vertical position when latched.

Other objects and advantages will be made more apparent as this description proceeds, particularly when considered in connection with accompanying drawings, in which:

Figure 1 is a longitudinal vertical cross-sectional view through the forward portion of a motor vehicle, and showing the hood latch therefor in elevation.

2

Figure 2 is a fragmentary plan view of the construction shown in Figure 1, taken on the line 2—2 of Figure 1.

Figure 3 is a cross-sectional view taken on the line 3—3 of Figure 1 and showing the latch mechanism in its closed or latched position.

Figure 4 is a cross-sectional view similar to Figure 3 but showing the latch in its open or unlatched position.

10 Figure 5 is a fragmentary cross-sectional view taken on the line 5—5 of Figure 1.

Referring now to the drawings, and particularly to Figure 1, the reference character 11 indicates the hood of a motor vehicle such as a truck. The hood covers the engine compartment of the vehicle and is hinged at its rearward edge in the conventional manner (not shown). At its forward end the hood 11 is provided with upper locking plate 12 extending between opposite sides of the hood and suitably secured thereto. Directly beneath the locking plate 12 of the hood in its closed position is a lower locking plate 13 forming a front structural member of the vehicle body and extending transversely thereof. The lower locking plate 13 carries a pair of transversely spaced rubber stops 14 engageable with the upper locking plate to limit downward movement of the hood and provide a resilient stop therefor.

15 30 35 40 45 50 55 A striker 16 in the form of a U-bolt is mounted upon the upper locking plate 12 in alignment with the longitudinal center line of the hood. The legs of the U-bolt extend through apertures in the upper locking plate and are adjustably secured thereto by nuts 17 to permit vertical adjustment of the U-bolt to vary the vertical position of the hood.

The lower locking plate 13 is formed with a transversely extending depression 18. The floor of the depression is formed with cross-shaped opening 19. The transversely extending portion of the cross-shaped opening provides clearance for the latch mechanism to be described hereafter, while the short longitudinally extending central portion forms an opening for the U-shaped striker 16 to project through into latching engagement with the latch mechanism.

Before describing the latch mechanism of the present invention, it is noted that the upper portion of the radiator grille 21 extends forwardly from the forward portion of the lower locking plate 13 and is spaced above the grille bar 22 to provide an opening 23 therebetween. This opening provides access to the manually operated release mechanism of the latch. A con-

ventional auxiliary hood catch 24 is provided, the catch being pivotally mounted upon a pair of L-shaped brackets 26 secured to the forward portion of the lower locking plate 13. A spring 27 urges the auxiliary catch 24 in a counter-clockwise direction to enable the catch to engage the shoulder 28 formed on the upper locking plate 12 carried by the hood. A safety catch is thus provided which may be manually released after the main latch mechanism is released and the hood raised a short distance.

The main hood latch is mounted upon a generally U-shaped bracket formed of a front lock plate 31 and a rear lock plate 32. The rear lock plate 32 is formed with a lower marginal flange 33 welded to the lower edge of the front plate 31 to secure the two plates together in a predetermined spaced relationship. The upper portions of the two plates are offset toward each other to form a narrow opening therebetween, the width of the opening being maintained by means of ears 34 bent rearwardly from the upper portion of the front plate 31 and engaging the forward face of the rear plate 32. Each of the plates is provided with a generally V-shaped notch 36 in its upper edge to provide clearance for the U-shaped striker 16. In addition, each of the plates 31 and 32 are formed with a pair of laterally spaced horizontally extending flanges 37 and 38 projecting from the upper edges of the plate. The flanges 37 and 38 are seated upon the floor of the depressed portion 48 of the lower plate 13 and are secured thereto by bolts 39. It will be noted that the plates 31 and 32 extend downwardly through the opening 48 formed in the lower locking plate.

It is best seen in Figures 3 and 4, a pair of cam members 41 and 42 are pivotally mounted between the front and rear plates 31 and 32 of the supporting bracket for pivotal movement about horizontal transversely spaced axes formed by rivets 43. Rivets 43 not only form pivots for the cam members, but also secure the front and rear plates 31 and 32 of the supporting brackets together in the proper spaced relationship determined by the ears 34. The spacing of the plates is such as to form a guideway for the cam members during their pivotal movement.

The cam members 41 and 42 have jaw portions 44 and 46 adapted to abut each other in the closed position of the hood latch as shown in Figure 3. In the open position of the hood latch shown in Figure 4, the jaw portions 44 and 46 of the cam members form a generally V-shaped entrance opening for the U-shaped striker 16. The two cam members 41 and 42 are also formed with integral interlocking projections 47 and 48 respectively. The projection 47 on the cam member 41 extends laterally beyond the edge of the jaw portion 44 and is separated therefrom by a shallow groove 49. Similarly, the projection 48 on the cam member 42 extends laterally beyond the edge of the jaw portion 46 and is separated therefrom by shallow groove 51 and a deep groove 52. In the closed position on the hood latch as shown in Figure 3, the two aligned shallow grooves 49 and 51 form a cavity for the reception and retention of the striker 16, while the deeper groove 52 in the cam member 42 provides clearance for the projection 47 of the cam member 41.

The cam member 41 is formed with a deep groove 53 beneath the projection 47 and with an extending tongue 54 beneath the groove

The tongue 54 is engaged by the end of a spiral spring 56, the inner end of which is anchored in a slotted stud 57. The spring 56 is tensioned in the locked position of the hood latch and upon release of the latch is effective to swing the cam member 41 in a clockwise direction. Inasmuch as the tongue 54 of the cam member 41 directly engages the projection 48 on the cam member 42, the latter is simultaneously swung in a counterclockwise direction and the parts are moved to the position shown in Figure 4 when the latch is released.

As best seen in Figures 1 and 5, a pair of L-shaped brackets 58 are spot welded to the forward plate 31 to form a support for a manually operable locking pawl 59 pivotally secured to the brackets by means of a pivot pin 61. A spring 62 encircles the pivot pin 61, the upper end of the spring being seated against the front plate 31 and the lower end engaging the lower end of the locking pawl 59 to constantly urge the pawl in a counterclockwise direction as viewed in Figure 1.

The lower arm 64 of the locking pawl 59 extends downwardly and forms a handle which may be manually operated by reaching through the opening 23 provided between the grille parts 21 and 22. The locking pawl 59 has an upwardly extending arm 66 engageable with the face of the front plate 31 to form a stop limiting the pivotal movement of the pawl. In addition, the locking pawl 59 also has a rearwardly extending locking flange 67 extending through aligned slots 68 formed in the front and rear plates 31 and 32 of the supporting bracket.

The cam member 42 is formed with a pair of teeth 69 and 71 along its lower edge. In the closed position of the latch mechanism as shown in Figure 3, the locking flange 67 of the locking pawl 59 is in engagement with the tooth 69 of the cam member to positively hold the two cam members in their closed position. Manual operation of the handle portion 64 of the locking pawl 59 to swing the locking flange 67 downwardly out of engagement with the tooth 69 permits the two cam members to be swung upwardly under the action of the spiral spring 56 to the open position shown in Figure 4. It will be noted that in this position the locking flange 67 of the locking pawl is engaged by the tooth 71 of the cam member 42 to limit the upward swinging movement of the cam members and to properly position them for subsequent movement to their closed position when the hood is again lowered.

It will be noted that in the open position of the hood latch as shown Figure 4, the projection 47 of the cam member 41 is in alignment with the normal path of the striker 16 so as to be engaged thereby during the closing movement of the hood. Should the hood be laterally displaced for any reason, the V-shaped opening formed by the jaw portions 44 and 46 of the cam members will guide the striker 16 toward a central position, and since the projection 47 extends substantially entirely across the bottom of the open guideway thus formed, the striker must necessarily engage the projection 47. Further downward movement of the hood and striker swings the cam member 41 downwardly, and simultaneously, through the interlock provided by projections 47 and 48, swings the associated cam member 42 downwardly. The striker is automatically centered in the cavity formed by the shallow grooves 49 and 51 in the two cam

5

members, this cavity being closed by the abutting jaw portions 44 and 46 at its upper side and by the projection 47 at its lower side to positively retain the striker in latched position.

A second spiral spring 73 is anchored to a pair of lugs 74 struck out from the rear plate 32. The free end of the spring is positioned to exert spring pressure upon the striker 16 in its latched position to prevent rattling.

The above described hood latch is extremely sturdy in construction, is formed of a relatively few easily manufactured parts, and is positive in operation. It automatically centers the hood and striker, permits a limited longitudinal movement of the hood and striker without interfering with the latching thereof, and is easily released by direct operation of the locking pawl from the forward portion of the vehicle. If desired, however, the handle portion 64 of the locking pawl 59 can be connected by a suitable Bowden cable control to the interior of the vehicle for remote operation. When unlatched, the spiral spring automatically raises the two cam members to their open position and simultaneously lifts the striker and hood connected thereto, upward movement of the hood being limited by the safety catch 24.

It will be understood that the invention is not to be limited to the exact construction shown and described, but that various changes and modifications may be made without departing from the spirit and scope of the invention, as defined in the appended claim.

What is claimed is:

In a motor vehicle having a pivotally mounted hood with a U-shaped striker depending therefrom and a body member beneath the forward end of said hood having an opening for the striker to pass through, a latch device comprising a U-shaped bracket having front and rear walls positioned beneath said body member and extending transversely of said vehicle in a ver-

6

tical plane, horizontal attaching flanges on the front and rear walls of said bracket attached to said body member, a pair of interlocked cam members pivotally mounted between the front and rear walls of said bracket about laterally spaced horizontal axes, jaw portions on said cam members engageable with said striker, a spring urged pawl pivotally mounted on one of the walls of said bracket and projecting through an elongated slot in said last-mentioned wall into the space between said walls, a ratchet tooth on one of said cam members engaged by said pawl to hold said cam members in striker retaining position, spring means acting upon the other of said members to simultaneously move said cam members toward their open unlatched position upon release of said pawl from said ratchet tooth, and a second tooth on said first mentioned cam member engaged by said pawl in the unlocked position of said cam members to limit their movement, said elongated slot permitting movement of said pawl between positions engaging said first and second teeth but preventing movement of said pawl to a point out of engagement with both of said teeth.

CLARENCE F. KRAMER.
